(57) **CLAIM**

The ornamental design for a display screen or portion thereof with graphical user interface, as shown and described.

DESCRIPTION

FIG. 1 is a front view of a first image in a sequence for a display screen or portion thereof with graphical user interface, showing our new design;

FIG. 2 is a front view of a second image in the sequence thereof;

FIG. 3 is a front view of a third image in the sequence thereof;

FIG. 4 is a front view of a fourth image in the sequence thereof; and,

FIG. 5 is a front view of a fifth image in the sequence thereof.

The appearance of the display screen or portion thereof with graphical user interface sequentially transitions between the images shown in FIGS. 1-5. The process or period in which one image transitions to another image forms no part of the claimed design.

In FIGS. 1-5, the outermost broken line illustrating the display screen and the intermediate rectangular broken line illustrating a display screen boundary form no part of the claimed design. The remaining broken lines illustrate portions of the graphical user interface that form no part of the claimed design.
